UNITED STATES PATENT OFFICE.

AUGUST LIEBHÄUSER, OF HOBOKEN, NEW JERSEY.

DESIGN FOR A BRACKET.

SPECIFICATION forming part of Design No. 24,174, dated April 2, 1895.

Application filed February 7, 1895. Serial No. 537,662. Term of patent 7 years.

To all whom it may concern:

Be it known that I, AUGUST LIEBHÄUSER, of Hoboken, Hudson county, New Jersey, have invented and produced a new and original Design for a Pot-Bracket, of which the following is a specification, reference being had to the accompanying drawing, which represents a perspective view of my newly-designed pot-bracket.

10 The leading feature of my design consists of a pot bracket having a pair of spaced and connected parallel arms that terminate at one end in connected simicircular jaws and at the other end in diverging curved sections.

15 *a, a*, represent the two connected parallel

arms of the pot bracket placed at a short distance from each other and terminating in semicircular jaws *a'*, that are connected at their free ends as at *a''*. Within the jaws *a'*, is arranged a concentric ring *c*, having radial claws *c'*. The rear ends of the arms *a*, diverge to form the curved sections *a''*, which are bent downward to form the vertical bars *a''*.

What I claim is—

10 The design for a pot bracket, substantially as shown.

AUGUST LIEBHÄUSER.
